UNITED STATES PATENT OFFICE.

WILLIAM W. LASKER, OF BROOKLYN, NEW YORK, ASSIGNOR, BY MESNE ASSIGNMENTS, TO POWERS ACCOUNTING MACHINE CORPORATION, OF NEW YORK, N. Y., A CORPORATION OF DELAWARE.

COUNTING SORTER FOR PERFORATED CARDS.

Application filed November 10, 1919. Serial No. 336,829.

This invention relates to machines for sorting cards into groups and for counting all the cards as they are presented for sorting, and for counting the cards as they are 5 passed to the individual groups.

Such a machine is shown in the U. S. Patent No. 1,312,807, issued to James Powers, Aug. 12th, 1919.

One of the objects of the present invention 10 is to improve generally the construction of such machines. Another is to adopt a counting mechanism for use with sorting machines similar to that shown in my U. S. Patent No. 1,815,370, issued September 9th, 15 1919.

As is well known to those skilled in this art, it is desirable to check up the operation 20 of group counters with the grand-total counter 38 or the sub-total counter. This is done by adding the totals of all of the group 25 counters and comparing the result with the number shown by the grand-total or sub-total counter as the case may be. When these agree, it is assumed that no error 30 has been made. With similar arrangements heretofore in use, the grand-total and sub-total counters were operated at each cycle of the machine, whether a card 35 was in the pin-box or not, thus showing a total which did not always represent the number of cards analyzed, and which 40 therefore did not always agree with the sum of the numbers shown by the group counters. Therefore, a particular object of 45 the invention is to provide means for counting the actual cards presented for sorting without stopping the machine if a card is 50 not presented or is misplaced, as contrasted with devices which merely count the complete cycles of the sorting machine during its operation and stop the machine if a card is presented wrongly or not at all. By the new arrangement no counting is made by the total counter unless a card is actually 55 properly presented for sorting and the machine is not stopped in the midst of a run.

Still another object of the invention is to 60 provide improvements in the arrangement whereby the series of individual counters and the counter for taking the sub-totals can be quickly and simultaneously zeroized to the exclusion of the grand-total counter.

A further object of the invention is to 65 provide an improved arrangement for dis-

abling the group counters and the sub-total 55 and grand-total counters when it is desired that the sorting machine sort the cards in the normal way without counting them.

Other objects of the invention will appear as the description proceeds; and while here- 60 in minute details of the invention are described, the invention is not limited to these, since many and various changes may be made without departing from the scope of the invention as claimed. 65

In the accompanying drawing, showing by way of example one of many possible embodiments of the invention,—

Figure 1 is a fragmental plan showing the counters and their connections with the 70 deflectors and the pin box;

Fig. 2 is a fragmental side elevation showing the counters, the pin box and intermediate connections;

Fig. 3 is an enlarged fragmental side ele- 75 vation showing the connection between the pin box and total-counters;

Fig. 4 is an enlarged fragmental side elevation showing the connection between the pin box and total-counters in inoperative po- 80 sition;

Fig. 5 is a transverse sectional view showing group counter connections and the zero- 85 izer for the counters;

Fig. 6 is a fragmental perspective view 85 showing the means for disabling the counters; and

Fig. 7 is a side elevation of a counter actuating arm.

Reference is made to the above men- 90 tioned patents for a general understanding of sorting machines and card counters; and particular reference is made to my said patent for an understanding of the construction and operation of a sorting machine to which 95 my present invention may be applied.

In my said patent there is shown a sorting machine having an analyzer frame, a deflec- 100 tor supporting frame secured to and forward of the analyzer frame, and an analyzer comprising a vertically reciprocatory pin box mounted on said analyzer frame and constituting a part of the analyzer into which cards are fed to be analyzed and sorted. Deflector shafts mounted transverse 105 to said supporting frame are provided with deflectors for deflecting, into appropriate compartments, cards conveyed from the

analyzer between lower guide rollers on said shafts and upper guide rollers resting on said lower rollers.

Referring particularly to Fig. 2 of the drawing annexed hereto, there is shown an analyzer frame 10, and a deflector supporting frame 11 secured to and forward of the analyzer frame. A vertically reciprocatory pin box 12 is mounted on said analyzer frame 10 and constitutes a part of an analyzer, not fully shown herein, into which cards are fed from a magazine, as shown in my said patent.

Deflector shaft supporting brackets 14 depend from said supporting frame 11 and carry deflector shafts 15 mounted in said brackets transverse to said supporting frame, said shafts in turn carrying deflectors 16.

Lower guide rollers 18 (Fig. 6) are mounted on said shafts, and upper guide rollers 20 rest on said lower rollers. Between these upper and lower guide rollers, cards pass from said analyzer and are deflected by the deflectors downwardly into appropriate compartments as shown in my said patent.

A horizontal supporting plate 23 (Fig. 5) is fixed on said frame 11 and disposed over some of said shafts 15 and provided with a series of elongated openings 24 (Fig. 1) above the level of said shafts. An upturned actuating arm 25 (Fig. 6) is fixed on the end of each shaft respectively, some of which project through the corresponding elongated openings 24. These arms are provided with an arcuate upper slot 27 (Fig. 7) each having the axis of its shaft 15 as its center of curvature.

A series of group counters 28 (Fig. 1), of ordinary construction, are mounted on said plate 23, one for each shaft; and each counter is provided at its inner end with an upturned counting crank 29 (Fig. 6) having a perforation in its outer end and spring pressed to normal position ready for actuation as is usual with such counters. A counting link 30 connects each counting crank with its corresponding actuating arm 25 and each comprises an outwardly hooked end portion 31 engaging in said perforation of the counting crank, and an inwardly hooked end portion 32 engaging in said arcuate slot 27 whereby when the deflector shafts are actuated in a direction which is clockwise on Fig. 6, for deflecting a card downwardly into the compartment, as explained in my said patent, the counters may be actuated. Since said arcuate slot 27 loosely receives the inwardly turned portion 32 it is thereby adapted to permit the arm to oscillate during deflection when the counting cranks are held stationary in actuated non-counting position for a purpose which will be explained. Collars 34 and 35 secured on the extremities of said end portions hold the links in place.

As the deflector is only actuated by a card in the analyzer, and as such card is deflected to its compartment by the actuated deflector, it will be seen that each time a card is deflected into any compartment, the corresponding counter is actuated and the number of cards passing into such compartment is thereby counted.

A sub-total counter 37 (Fig. 1) and a grand-total counter 38 are provided for counting the cards analyzed in the analyzer. The means for actuating these total counters will now be described.

At one end of the pin box 12 (Fig. 1) there is provided an inwardly pointed lug 40 having therein a vertical guide bore 41 in which a plunger rod 42 (Fig. 3) is vertically slidable. This rod is provided at its lower end with a feeler plate 44 (Figs. 1 and 3) adapted to engage over an edge of the card to be sorted when the card is properly placed in the analyzer. A spring 45 disposed on said rod between said lug and feeler plate is adapted, when the pin box is depressed, to press said feeler plate to a normal position against a card in the analyzer; but if no card be present in the analyzer, the spring will depress the plate still lower to an abnormal position as shown in Fig. 4. An elbow lever 46, pivoted at its elbow part on said frame 10 near the receiving or rear side of the analyzer, has an upturned active arm 47, and a motive arm 48, the latter engaging under said feeler plate 44, thereby to rock said active arm forward to an abnormal position, as in Fig. 4, when said plate is lowered to abnormal position as explained. A counting lever 50 has its forward end pivotally connected to a depending link 51 pivotally connected to the rear end of an intermediate lever 52 intermediately fulcrumed as at 53 (Fig. 2) near the rear end of said supporting frame 11. A shoulder plate 55 fixed to the forward side of the pin box 12 is provided near one end with a shoulder slot 56 receiving said counting lever 50 and having a shoulder 57 at its upper part. Said counting lever is pivoted at its rear end to said upturned active arm 47 and is provided at its intermediate part with an abutment 60 adapted when said active arm is held by the spring 53 in normal rearward position, as when a card is in the analyzer, to engage under said shoulder 57, as in Fig. 3, to be depressed and actuated on the downward movement of the pin box. When the active arm is rocked forwardly to abnormal position, as when there is no card in the analyzer, said abutment will escape from said shoulder and thereby be free from such actuation, as in Fig. 4.

The sub-total counter 37 is at the rear of said series of group counters; and the grand-total counter 38 is disposed to the rear of the sub-total counter and has an upturned

counting crank 62 (Figs. 3 and 6). The sub-total counter has a triangular counting crank 63 having a lower rear pivot point 64 linked, by the link 65 (Fig. 3), to the forward end of said intermediate lever 52. The triangular crank has also an upper pivot point 66 (Fig. 6) above the counting shaft 68 of the sub-total counter. A synchronizing link 70 connects the upper end of said upturned counting crank 62 with said upper pivot point 66 and is provided with a downturned hook 71 (Fig. 3) at its forward end for a purpose which will be explained.

From the foregoing it will be seen that when there is a card in the analyzer and the pin box is lowered, the card holds the feeler plate up and the active arm 47 and the counting lever back, as in Fig. 3, so that a downward movement of the pin box causes the shoulder 57 to depress the counting lever and raise the link 65 and rock forward the triangular crank and the upturned crank 62 connected to the triangular crank by the synchronizing link 70. On the other hand, if, by improper feeding, exhaustion of the card supply, or for other reasons there is no card in the analyzer, on the lowering of the pin box the feeler plate 44 will move to the lower abnormal position shown in Fig. 4, and the active arm 47 and the counting lever 50 will be rocked forwardly so that the abutment 60 escapes the shoulder 57; and the counting lever 50 and the total counters will not be actuated.

An important function of the machine herein described is that it permits the cooperation of the group counters 28 with the grand-total counter 38 or the sub-total counter 37 for the checking up of their accuracy. This is done by adding the totals of all of the group counters and comparing the sum with the number shown by the grand-total counter 38 or sub-total counter 37 as the case may be. When these agree, it is assumed that no error has been made. With similar arrangements heretofore in use, the grand-total and sub-total counters were operated at each cycle of the machine, whether a card was in the pin-box or not, thus showing a total which did not always represent the number of cards analyzed.

The counters are placed close together on the plate 23 for reasons of economy of construction and ease of observation; and the plate 23 need extend only part of the length of the frame 11, and over some of the shafts 15 as hereinbefore stated.

At times, as after a run of cards, it may be desirable to zeroize all of the group counters and the sub-total counter, and special means for doing this have been devised. A zeroizing gear 73 (Fig. 2) is provided at the outer end of each group counter and the sub-total counter. Depending at the outer edge of said supporting plate 23 (Fig. 5) there are

provided supporting brackets 74 on one of which is mounted a drive gear shaft 75. Grooved wheels 76 are carried by the other of said brackets. A drive gear 77 (Fig. 2) and a drive crank 78 are mounted on said gear shaft; and a zeroizing rack 79 slidably carried on said wheels in the grooves thereof is provided at its upper edge with rack teeth 80 engaging said zeroizing gears 73, and at its lower edge with rack teeth 81 engaging said drive gear 77. When it is desired to zeroize the group and sub-total counters, it is only necessary to revolve the crank 78 backward and then forward until the counters are zeroized. A separate zeroizing milled-head 85 (Fig. 1) is provided on the outer end of the grand-total counter, since this counter is not usually zeroized at the end of each group-run, but is usually zeroized after longer intervals, for instance, at the close of a day or at the end of the whole job.

Sometimes it is not necessary or desirable to have the counters to count, and for such circumstances, means are provided for disabling or cutting out of operation all of the counters. Forward and rear guide bolts 87 and 88 (Fig. 2) are mounted on the outer face of said supporting frame over said supporting plate, and carrying thereon a horizontal disabling bar 90 provided with guide slots 91 received on said guide bolts, and with receiving slots 92 (Fig. 6) loosely receiving said outturned ends 31 of the counting links, being thereby disposed between the links 30 and the counting arms 29. A connecting pin 93 at the rear of said bar is adapted to engage said downturned hook 71, so when the bar is drawn forward (leftward of Fig. 2), the synchronizing link 70 is also drawn forward. A detent pin 94 (Fig. 2) is provided on the disabling bar; and a disabling lever 95 pivotally mounted on said forward guide bolt 87 is provided with a cam-lug 96 adapted to engage and lock upon said detent pin 94 and cause said disabling bar and said synchronizing link to draw and hold the counting cranks 29, 62 and 63 forward to non-counting position. When the cranks are thus drawn, the abutment 57 is held down and the counting lever 50 cannot be actuated by the downward movement of the pin box. Also the cranks 29 and links 30 are held forward and cannot be actuated by the actuating arms 25, the slots 27 permitting the actuating arms, the shafts 15 and the deflectors to oscillate normally when the links 30 are thus drawn forward. When the bar 90 is in released position, as shown by full lines of Fig. 2, the synchronizing link 70 may still rock backward or forward, as shown in Figs. 2 and 3. Also, because of the length of the receiving slot 92 (Fig. 6) the counting cranks 29 may oscillate normally.

I claim:

1. In combination, a reciprocatory element; a feeler adapted to press against a card if presented thereto, or to move to a different position if a card be not presented; an intermediate lever operated by said feeler, but normally disconnected therefrom if a card be presented; a counting member moved by the intermediate lever when a card is presented to position to be actuated by said element and when the card is absent to escape from such actuation; and a counter operatively connected with the counting member.
2. In a sorting device having a plurality of compartments and a deflector for each compartment, a counter for each compartment having a crank; a connection between a deflector and the crank of the counter for

its compartment comprising a slot; a disabling bar provided with slots loosely receiving said connections between the deflectors and the cranks of the counters; and means for moving the disabling bar and the cranks of the counters to non-counting position.

3. In a sorting device having a plurality of compartments and a deflector and a counter for each compartment, a pin box operatively connected with said deflectors and said counters whereby a card may cause a deflector to be set and the corresponding counter to be operated, and means comprising a disabling lever for disconnecting said pin box and said counter, whereby said pin box may cause said deflectors to operate independently of said counters.

WILLIAM W. LASKER.
